UNITED STATES PATENT OFFICE.

SEBASTIAN ZIANI DE FERRANTI, OF BASLOW, ENGLAND.

STEAM-SUPERHEATING.

1,319,699.

Specification of Letters Patent. Patented Oct. 28, 1919.

Application filed April 19, 1913. Serial No. 762,352.

To all whom it may concern:

Be it known that I, SEBASTIAN ZIANI DE FERRANTI, a subject of the King of Great Britain and Ireland, and residing at Baslow, 5 in the county of Derby, England, have invented certain new and useful Improvements in and Relating to Steam-Superheating, of which the following is a specification.

The invention relates to steam superheating and particularly to superheaters working in conjunction with water-tube boilers.

The main objects of the invention are to provide for the efficient transference to the superheater elements of a large proportion 15 of the heat energy contained in the furnace gases while at the same time arranging for the superheater elements to be more or less by-passed for regulation of the superheating particularly when starting up and stopping.

20 With this object, the invention consists in a boiler comprising an upper steam drum with one or more water drums connected thereto by water tubes and provided on at least one side of the steam drum with separate ducts for the furnace gases, one or more of such ducts each containing a screen of water tubes in front of superheater elements and a damper beyond the superheating elements and another or others of such ducts 25 containing water tubes only to form a comparatively small superheater by-pass for the furnace gases.

If the boiler is single-sided, the superheater and by-pass ducts are necessarily arranged on the same side of the steam drum; if, however, the boiler is double-sided, both superheater and by-pass ducts may be arranged on each side or superheater and by-pass ducts on one side only, and superheater 30 ducts alone on the other side.

The invention also consists in the superheating arrangements and applications thereof hereinafter described or indicated.

Referring to the accompanying drawings: 45 Figure 1 is a sectional elevation illustrating the application of the invention to a reheating turbine.

Fig. 2 is a sectional plan of a boiler and superheater installation having superheaters 50 working at different pressures.

Fig. 3 is a sectional view on line 8—8 of Fig. 2.

Fig. 4 is a section on line 9—9 of Fig. 2 and,

55 Fig. 5 is a side elevation with the casing wall removed.

The drawings are of a diagrammatic nature and are not intended to give such information as is common knowledge to those skilled in the art; when desirable the same 60 reference symbols are employed to denote corresponding parts.

Referring more specifically to these drawings which illustrate a boiler and superheater installation having superheaters working at 65 different pressures and which may be employed for example in combination with a reheating turbine system as shown in Fig. 1, as regards the arrangement of superheaters themselves, a high pressure and an intermediate pressure superheater are shown on the right-hand side of the boiler and a low pressure superheater only on the left-hand side. The high pressure superheater 70 consists of tubes, d^1 , passing from a header, e^1 , to a header, f^1 , while the intermediate pressure superheater on the same side comprises tubes d^2 , passing from a header, e^2 , to a header, f^2 . All the headers as seen in Fig. 5 are less in length than the length of 75 the boiler itself, while the headers, e^1, f^1 , are in staggered relationship to the headers, e^2, f^2 , so that the header ends may be accessible. On the left-hand side of the boiler, the low pressure superheater is arranged comprising 80 tubes, d^3 , passing from a header, e^3 , to a header, f^3 , this superheater in accordance with the invention working in conjunction with some only of the water tubes, c , the remainder being associated with additional 85 tubes, i . The uptakes are arranged as before so as to form four ducts, each controlled by its damper, superheaters being arranged respectively one in each of three of said 90 ducts and water tubes alone in the fourth. The installation may be applied to a turbine 95 which is shown in Fig. 1 and is divided into three separate stages, through which steam passes successively, the steam being superheated not only initially but also before its inlet to each succeeding stage.

The course of the steam through the different parts of the installation is as follows: From the steam drum, a , the steam passes through the pipe, h^1 , to the saturated steam 105 header, e^1 , of the high pressure superheater, thence through the superheater tubes, d^1 , to the superheated steam header, f^2 , and through a pipe 2, to the first stage t^1 , of the turbine. After expanding in this stage, 110 steam leaves by the pipe, 3, and passes to the saturated steam header, e^2 , of the interme-

diate superheater, through its tubes, d^2 , to the superheated steam header, f^2 , and so by a pipe, 4, to the second stage, t^2 , of the turbine. After doing work in this stage, steam 5 passes through the pipe, 5, to the low pressure superheater and after superheating therein reaches the third stage, t^3 , of the turbine, through the pipes 6, leaving this stage on its way to the condenser or else- 10 where by the pipe 7.

In such a re-heating installation it will be seen that between comparatively wide limits the degree of superheat in any or all of the superheaters may be varied or one or more 15 of them may be cut out entirely if desired.

In some cases either the initial superheater or one or more of the reheaters may be omitted entirely.

It is advisable whatever the precise arrangement of additional heat absorber adopted that a section of it at least should be disposed in each duct so that the gases are in every case cooled to the greatest possible extent before coming into contact with the 20 dampers.

Although certain specific examples of the invention have been described in detail by way of illustration it will be evident that the principle on which it is based can be 30 embodied in a variety of different structural forms.

Having now described my invention what I claim as new and desire to secure by Letters Patent is:—

35 1. The combination with a motor element including a plurality of sections wherein the motive fluid undergoes progressive expansion, of means for superheating the motive fluid prior to its discharge into each 40 of said sections, said means comprising a boiler element including a steam drum and superheating elements in series with said motor sections, one another and said steam drum, and means for independently controlling 45 the supply of heating products to the superheaters.

2. In combination with boiler elements substantially as described, pressure superheating elements in series therewith and 50 with each other and differentially controlled ducts for the heating products in which ducts the elements are located.

3. In combination, boiler elements, high, intermediate and low pressure superheater elements in series therewith and with one another for supplying superheated steam at different pressures and temperatures and differentially controlled ducts in which said elements are disposed.

60 4. In combination, in a boiler, steam and water drums connected by water tubes, a grate, a boiler casing and partitions dividing said casing into flue compartments

through which the flue gases pass in parallel streams and superheater elements designed 65 to receive steam at different pressures and disposed in certain of said compartments, said superheater elements being arranged in series with one another.

5. In combination, in a boiler, steam and 70 water drums connected by water tubes, a grate, a boiler casing and partitions dividing said casing into flue compartments, superheater elements designed to receive steam at different working pressures, said superheater elements being disposed in certain of 75 said compartments and being in series with the water tubes and with one another and damper means controlling the outlets from said flue compartments.

6. In combination, in a boiler, steam and water drums connected by water tubes, a grate, a boiler casing and partitions dividing said casing into flue compartments, additional water tubes in one of said compartments, superheater elements each located in one of the other compartments, said superheater elements being adapted to receive steam at different working pressures, said superheater elements being connected in series with one another and damper means for independently controlling the outlet 90 from the flue compartments.

7. A Yarrow-type water-tube boiler including a grate, and a plurality of superheater elements designed to receive steam at different working pressures, said superheater elements being disposed on the side 95 of the water tubes of the boiler remote from the grate, and being connected in series.

8. A Yarrow-type water-tube boiler including a grate, and a plurality of superheater elements designed to receive steam at different working pressures, said superheater elements being disposed on the side 100 of the water tubes of the boiler remote from the grate, and being connected in series, and means for varying as to each superheater the relative flow of hot gases from the grate to the superheater.

9. In combination, boiler elements, superheater elements in series therewith and with each other and designed to receive steam at different working pressures, a series of ducts, one of said ducts containing boiler 115 elements only and the others the superheater elements, the duct containing the boiler elements serving as a by-pass, substantially as described.

In testimony whereof, I affix my signature in presence of two witnesses.

SEBASTIAN ZIANI DE FERRANTI.
